SAFETY CONTROL FOR GASEOUS FUEL
BURNERS

Thomas H. Jeffers, Lynwood, Calif., assignor to
Grayson Heat Control, Ltd., Lynwood, Calif.,
a corporation of California

Application October 31, 1941, Serial No. 417,304

12 Claims. (Cl. 158—117.1)

This invention relates to safety devices for gaseous fuel burners and, more particularly, to safety controls intended to shut off the supply of fuel to a gas appliance should the pilot burner become accidentally extinguished.

An object of the invention is to cause complete and automatic shut-off of all fuel to both the main and pilot burners when the pilot burner becomes extinguished.

Another object of the invention is to permit fuel to flow to the pilot burner during starting operation while preventing any flow to the main burner.

Another object of the invention is to prevent flow of fuel to either the main or pilot burners when the appliance is unattended unless the safety device is operative.

Another object of the invention is to maintain the pilot burner in continuous operation, regardless of whether or not fuel is flowing to the main burner.

Another object of the invention is to reduce the number of parts by controlling both the main burner and the pilot burner fuel supply by a single valve.

Another object of the invention is to utilize positive snap-acting means for accomplishing the shut-off.

Another object of the invention is to arrange the control in compact form as a unitary construction which is adapted for manufacture at low cost and which will occupy the minimum of space when installed in the gas appliance.

Other objects and advantages will become apparent from the following description taken in connection with the accompanying drawings, wherein:

Fig. 1 is an end elevation of the safety control;

Fig. 2 is a section taken on the line 2—2 of Fig. 1 looking in the direction indicated by the arrows;

Fig. 3 is a sectional but semi-developed view illustrating the location of the various parts in relation to the path of travel of the fuel through the control;

Fig. 4 is a partial section taken on the line 4—4 of Fig. 1 looking in the direction indicated by the arrows;

Fig. 5 is a partial section taken on the line 5—5 of Fig. 1 looking in the direction indicated by the arrows;

Fig. 6 is a partial section taken on the line 6—6 of Fig. 1 looking in the direction indicated by the arrows;

Fig. 7 is a partial section corresponding to Fig.

4 but showing the main control valve in a different position;

Fig. 8 is a partial section corresponding to Fig. 5 but showing the main control valve in a different position;

Fig. 9 is a partial section corresponding to Fig. 6 but showing the main control valve in a different position;

Fig. 10 is a cross-section through the control shown in Fig. 1;

Fig. 11 is a plan view of the dial;

Figs. 12 and 13 are geometrical developments of the seating surfaces of the main control valve.

Referring more particularly to the drawings, 15 the control device comprises a casing 10 having an inlet 12 in one side thereof communicating with a centrally disposed chamber 14 extending substantially perpendicular to the inlet. The upper portion of the chamber 14 is threaded for the reception of a cap 16 which serves to close the open end of the chamber.

A valve seat member 18 is positioned within the chamber 14. The valve seat member is generally cylindrical in form having an upper 25 threaded portion engaging the threaded portion of the chamber 14 below the cap 16 and an unthreaded portion closely fitted within the lower portion of the chamber 14 with its bottom face seated upon the bottom portion 20 of the chamber.

A recess 22 is provided in the bottom face of the valve seat member 18 and an annular knife-edge portion 24 projects inwardly thereof to form a seat for a snap disc 26. The snap disc is 35 smaller in diameter than the recess 22 and assumes a convex form, as in Fig. 3, when free. The disc is supported in the recess 22 by a thrust element 28 provided on one face with an annular knife-edge portion 30 similar to the portion 24.

40 In this embodiment, the knife-edge 24 is smaller in diameter than the knife-edge 30 and is thus positioned inwardly thereof with respect to the disc 26 to provide the necessary leverage for operation. When pressure of the thrust element 28 is relieved the snap disc tends to force its center portion away from the thrust element to form the convex curve mentioned, thus being in the opposite position to that shown in Fig. 2.

The disc 26 and thrust member 28 are slidably 50 supported within the recess 22 and receive axial thrust from the rounded end 34 of the rod portion 32 of a thermally responsive element, causing the disc 26 to assume the position shown in Fig. 2. The thermally responsive element may be of the rod-and-tube type having a tube 34

of material having a high coefficient of expansion and the rod 32 having a relatively lower coefficient of expansion. The rod 32 is supported at each end in recesses formed in the thrust element 28 and tube 34. The element is supported from the casing 10 by the tube portion which threadedly engages a projection 36 thereon and is secured by means of the lock nut 38.

The valve seat member 18 is provided with an annular opening 40 therein extending from the upper end thereof and terminating adjacent the recess 22. A plurality of apertures 42 extend transversely through the wall of the valve seat member 18 intermediate its ends and afford communication between the annular passage 40 and the chamber 14. A pair of oppositely disposed holes 45 may be formed in the end wall between the opening 40 and the recess 22 for the reception of a tool for inserting the valve seat member 18 in position.

An annular projection is formed on the upper surface of the valve seat member 18 and serves as a valve seat 44 for a safety valve member 46. The safety valve 46 is adapted to control the passage of fuel between the chamber 14 and the apertures 42 in the valve seat member by movement toward and away from its seat 44. To this end, the safety valve 46 is provided with a valve stem 48 slidably engaging an axial opening 49 in the valve seat member 18 and carrying a threaded projection 50. The projection 50 engages the snap disc 26 at its central portion on the side opposite the thrust element 32 and is adjustable with respect thereto due to its threaded engagement with the valve stem. A coil spring 52 extends between the safety valve 46 and the underside of the cap 16 and assists the valve member 46 in returning to its seat when the snap disc 26 permits. It will be understood that the snap disc 26 is capable of opening the safety valve 46 against the force of the fuel pressure in the chamber 14 and the force of the spring 52.

A tapered valve seat 54 is formed in the casing 10 substantially perpendicular to the chamber 14 with which it communicates at its smaller end by means of a passage 56 between the valve seat member 18 and the smaller end. Intersecting the tapered valve seat 54 intermediate its ends is an outlet 58 which extends through the casing on the side opposite the inlet 12. As will be clear from Fig. 10 the inlet 12 and outlet 58 are in different horizontal planes and there is no communication between the inlet and the passage 56 except by way of the safety valve chamber 14. Engaging with the tapered valve seat 54 is a tapered plug cock or main control valve 60 having an axial opening 62 extending from the smaller end thereof and communicating with a transverse port 64 extending through one side thereof intermediate the ends. The axial opening 62 is in communication with the passage 56 in the casing 10 and the port 64 is adapted to establish communication between the opening 62 and the outlet 58 when the plug cock is rotated to certain position in its seat 54.

The plug cock or main control valve 60 is held yieldably against its seat by a spring 66 housed within a recess in the upper end thereof and engaging with a retainer plate 68 secured to the casing 10 as by means of the screws 70. An operating stem 72 projects from the upper end of the main control valve 60 and is provided with an operating handle in the form of a dial 74 fixedly

secured thereto and providing means by which the valve 60 may be rotated in its seat 54.

In order to limit rotation of the valve 60 to substantially 180°, the retainer 68 is provided with a projection 76 extending perpendicular thereto and received within a groove 78 of arcuate form in the underside of the dial 74. The arcuate groove 78 is made of sufficient length to permit the specified amount of rotation of the valve 60 and the projection 76 forms a stop which will engage with either end of the groove to limit such rotation. The face of the dial 74 is provided with suitable indicia for "on," "pilot only" and "off" positions which are adapted to be aligned with a notch 75 formed in the casing 10 adjacent the retainer. The groove 78 is arranged to limit the rotation of the valve 60 between the "on" and "off" positions by engagement with the stop 76. At the "pilot only" position a non-positive stop is provided. This stop is in the form of a plunger 81 yieldably mounted within the dial 74 and projecting from the underside thereof into engagement with the retainer 68. At the "pilot only" position the end of the plunger 81 drops into a depression formed in the retainer 68 with an audible click. Furthermore, the plunger 81 adds a noticeable resistance to the rotation of the dial when moved from the "pilot only" position.

The safety valve of this invention not only provides control of the fuel passing through the outlet 58 to the main burner but also provides control of the passage of fuel to a pilot burner incorporated in the control. Accordingly, a passage 80 is formed in the casing communicating with the tapered valve seat 54 of the main control valve or plug cock 60. At the junction of the passage 80 with the valve seat 54 is an elongated slot 82 formed in the casing and extending partly on each side of the passage 80 around the valve seat 54 for a short distance. The slot 82 is adapted to register with a groove 84 in the valve 60 extending tangentially from one end of the port 64 through the wall of the valve and affording communication between the slot 84 and the passage 62.

The other end of the passage 80 in the casing 10 communicates with a bore 86 formed in the casing and within which a pilot adjusting member 88 is rotatably mounted. The upper end of the pilot adjusting member 88 projects into an enlarged portion of the bore 86 at the exterior of the housing 10 and is provided with a slot 90 by means of which the member may be rotated in the bore. The enlargement may be threaded for the reception of a closure cap 92 which is removable for obtaining access to the pilot adjusting member 88 when required. A T-shaped opening 94 is formed in the lower end of the pilot adjusting member 88 and establishes communication between the passage 80 and a passage 96 in the housing leading to a threaded connection 98 for a pilot burner 100. The pilot burner 100 extends from the housing 10 substantially parallel with and adjacent to the thermally responsive element 34 so that the terminal end of this element will be heated by the pilot flame.

It will be observed that passage of fuel to the pilot burner 100 can be obtained from the inlet 12 when the groove 84 registers with the passage 80 and the safety valve 46 is opened. In order to provide for passage of fuel to the pilot burner 100 when the safety valve 46 is closed, such as for starting purposes, a by-pass is provided in this construction. This by-pass takes the form of an angular passage 102 extending from the inlet 12

to the valve seat 54 of the main control valve or plug cock 60. The junction of the passage 102 with the valve seat 54 is in longitudinal alignment with the junction of the passage 80 therewith and these passages are spaced in such relationship that both are within the margin of the port 64 when in registry therewith.

The passage of fuel through the by-pass 102 is controlled by a manually operated pilot control valve carried by the casing. The pilot control valve may comprise a valve head 104 provided with a stem 106 projecting from the casing 10 and carrying a button 108 by means of which it may be operated. The valve head 104 engages with a valve seat 110 formed on the inner end of a valve chamber 112, the opposite end of which is sealed against leakage by a closure cap 114 and gasket 116. A spring 118 extends between the valve head 104 and the closure cap 114 and serves to maintain the valve member in engagement with its seat 110. Leakage of fuel along the valve stem is prevented by the provision of a packing 120 compressed into engagement with the valve stem 106 by means of a spring 122 coacting with a closure cap 124 secured to the casing below the button 108. As shown in Fig. 3, the fuel passing from the inlet flows through one leg of the angular passage 102 into the valve chamber 112 and, upon movement of the pilot control valve to open position, such fuel will travel along the other leg of the angular passage 102 to the tapered valve seat 54 of the main control valve or plug cock 60. Upon release of manual pressure upon the button 108 the spring 118 will return the valve head 104 to its seat and close the by-pass passage.

The operation of the device is as follows: Fuel from the inlet 12 is contained in the safety valve chamber 14 above the safety valve 46 which is in closed position in engagement with the seat 44. Ordinarily, there is provided a shut-off cock in the fuel line ahead of the control described herein which is normally left open and forms no part of the present invention. However, should it be desired to remove the closure cap 16 to clean or repair the safety valve assembly then the fuel line shut-off cock would be closed as a preliminary operation.

Assuming that the fuel is flowing through the inlet as described, the dial 74 of the main control valve is rotated to "pilot only" position and the button 108 is depressed to operate the pilot control valve. This permits fuel to flow from the inlet 12 through passage 102 and past the pilot control valve head 104 to the main control valve seat 54. As the main control valve is in "pilot only" position the port 64 therein is in registry with the passage 102 as well as the passage 80, as shown in Figs. 4-6 inclusive. As the outlet 58 to the main burner is not in registry at this time with the passage 62 there is no exit for the fuel entering the passage 62 except through the passage 80. Fuel then flows through the latter passage 80 to passage 96 in an amount controlled by the adjustment of the pilot adjustment member 88. The fuel flowing from the pilot burner tip is then ignited with a match or other suitable means. The flame is arranged to impinge properly on the outer end of the tube element 34, as familiar to those skilled in the art, by adjustment of the pilot adjustment member 88.

After the button 108 has been depressed for a short period, usually two minutes, the pilot burner flame heats the thermal element sufficiently to expand the tube portion 34 thereof and

move the outer end thereof slightly toward the right as viewed in Fig. 2. Due to the lower coefficient of expansion of the rod portion 32 the pressure thereof on the thrust element 28 is relieved, thus removing the thrust exerted by the latter upon the snap disc 26. Hence, the snap disc 26 finally snaps over center to its normal position as shown in Fig. 3. The movement of the snap disc 26 actuates the threaded element 50 to move the safety valve 46 off the valve seat 44 against the pressure of the fuel in chamber 14 and the spring 52.

Upon opening of the safety valve 46 fuel may flow through the passage 56 into the axial opening 62 of the main control valve 60. Fuel also passes through the port 64 and the passage 80 to the pilot burner instead of being by-passed from the inlet 12 around the safety valve 46 as was the case before this valve was opened. Thus, the release of the button 108 to close the pilot control valve after the safety opens does not cut off the flow of fuel to the pilot burner but merely closes the by-pass passage from the inlet 12. The main control valve is then rotated to the "on" position shown on the dial 74 as limited by the stop 76. In this position the port 64 registers with the outlet 58, as shown in Figs. 7-9 inclusive, and permits fuel to flow to the main burner to be ignited at that point. The supply of fuel, however, is not cut off to the pilot burner due to the provision of the groove 84 in the main control valve 60 which connects the axial opening 626 therein with the elongated slot 82 of the passage 80. It will be observed that the passage 102 is at this time closed off by the surface of the main control valve 60.

Should the pilot burner flame become extinguished when the main burner is operating under control of the safety valve as described, the cooling of the thermally responsive unit 34 would cause reversal of the position of the snap disc 26 and immediate closing of the safety valve 46. As both the main and pilot burners are at such time being supplied with fuel by way of the passage 56 under control of the safety valve, no further fuel would flow to either burner. Thus, a complete shut-off of fuel is obtained upon operation of the safety valve.

The main burner may be turned off and the pilot flame left burning by rotation of the main control valve dial from the "on" to the "pilot only" position. Both burners may be extinguished and the appliance rendered inoperative by rotating the dial to the "off" position. In this position, the port 64 is diametrically opposite the outlet 58 which is thus closed and the by-pass passages 102 and 80 are also closed off by the surface of the main control valve 60.

In the "on" position of the main control valve dial the by-pass passage 102 is closed and manual pressure on the button 108 could not by-pass fuel around the safety valve in this position. Thus, no fuel can be made to flow to the main burner until the pilot burner has been lighted a sufficient time to cause opening of the safety valve as described. When the appliance is left unattended no fuel can flow to either burner unless the safety valve has previously been brought into operation to shut off the fuel supply should the pilot burner become extinguished.

The pilot control valve provides means for preventing supply of fuel to the pilot burner in the event that the main control valve is left in "pilot only" position and the pilot flame becomes extinguished. It will be apparent that even if

the safety valve operated under these conditions it would be ineffective to shut off the pilot burner fuel supply by way of the by-pass passages. Hence, the pilot control valve forms an additional safety feature.

I claim:

1. A safety control for gaseous fuel burners having main and pilot burners, comprising in combination, a safety valve controlling a common passage for fuel to both the main and pilot burners, a main control valve having a port adapted to communicate with said passage, separate outlets for fuel to the burners under control of said main control valve, said main control valve being adjustable to a position permitting flow of fuel through said port and one of said outlets to the pilot burner when the safety valve is in closed position and preventing flow of fuel to the main burner in said position, means communicating with said port and said one outlet for by-passing fuel around said safety valve to the pilot burner when the main control valve is in said position, and means responsive to the presence of a flame at the pilot burner for opening the safety valve for flow of fuel through said common passage and through said port and said one outlet to the pilot burner instead of by way of the by-pass while said main control valve remains in said position.

2. A safety control for gaseous fuel burners having main and pilot burners, comprising in combination, a safety valve controlling a common passage for fuel to both the main and pilot burners, a main control valve having a port adapted to communicate with said passage, separate outlets for fuel to the burners under control of said main control valve, said main control valve being adjustable to a position permitting flow of fuel through said port and one of said outlets to the pilot burner when the safety valve is in closed position and preventing flow of fuel to the main burner in said position, means communicating with said port and said one outlet for by-passing fuel around said safety valve to the pilot burner when the main control valve is in said position, a manually operated auxiliary valve movable between positions for controlling the passage of said by-passed fuel and being biased to a closed position, and means responsive to the presence of a flame at the pilot burner for opening the safety valve for flow of fuel through said common passage and through said port and said one outlet to the pilot burner instead of by way of the by-pass while said main control valve remains in said position, whereby said auxiliary valve may be closed under said bias thereof.

3. A safety control for gaseous fuel burners having main and pilot burners, comprising in combination, a safety valve controlling a common passage for fuel to both the main and pilot burners, a main control valve having a port adapted to communicate with said passage, separate outlets for fuel to the burners under control of said main control valve, said main control valve being adjustable to a position for permitting flow of fuel through said port and one of said outlets to the pilot burner when the safety valve is in closed position and preventing flow of fuel to the main burner in said position, said main control valve being adjustable to another position permitting flow of fuel through said common passage and said port and outlets to both main and pilot burners when the safety valve is in open position, means communicating

with said port and said one outlet for by-passing fuel around said safety valve to the pilot burner when the main control valve is in the first said position, and means responsive to the presence of a flame at the pilot burner for opening the safety valve for flow of fuel through said common passage and through said port and said one outlet to the pilot burner instead of by way of the by-pass while the main control valve remains in first said position.

4. A safety control for gaseous fuel burners having main and pilot burners, comprising in combination, a casing having an inlet for fuel and separate outlets therefor leading to the main and pilot burners, a valve seat dividing said inlet from said outlets, a safety valve engageable with said seat for controlling flow of fuel from said inlet through said outlets to both the main and pilot burners, a main control valve between said safety valve and outlets having a port therein, said main control valve being movable to a position permitting the passage of fuel from the safety valve through said outlets and said port to both the main and pilot burners, a by-pass passage in said casing providing communication through said port and one of said outlets between said inlet and the pilot burner when the safety valve is closed and said main control valve is moved to another position, and means responsive to the presence of a flame at the pilot burner for opening the safety valve, said port being positioned out of communication with said by-pass passage when the main control valve is thereafter moved to the first said position.

5. A safety control for gaseous fuel burners having main and pilot burners, comprising in combination, a casing having an inlet for fuel and an outlet therefor to the main burner, a safety valve controlling the passage of fuel between the inlet and outlet, a main control valve in said casing between said safety valve and the outlet and adjustable between "off" and "on" positions to control the passage of fuel therebetween, a duct in said casing communicating with said inlet and the pilot burner for by-passing fuel around said safety valve to said pilot burner, said duct being controlled by said main control valve, and means responsive to the presence of a flame at the pilot burner for opening said safety valve for passage of fuel to both the main and pilot burners when said main control valve is adjusted to said "on" position.

6. A safety control for gaseous fuel burners having main and pilot burners, comprising in combination, a casing having an inlet for fuel and an outlet therefor to the main burner, a safety valve controlling the passage of fuel between the inlet and outlet, a main control valve in said casing between said safety valve and the outlet, means for adjusting said main control valve between "off" and "on" positions and a position intermediate thereto, said main control valve being adapted to permit the passage of fuel from the safety valve to both the main and pilot burners when in said "on" position and to the pilot burner only when in said intermediate position, means operable in said intermediate position of the main control valve for conducting fuel to the pilot burner when the safety valve is closed, and means responsive to the presence of a flame at the pilot burner for opening the safety valve for passage of fuel therethrough to said pilot burner while the main control valve remains in said intermediate position.

7. A safety control for gaseous fuel burners having main and pilot burners, comprising in combination, a casing having an inlet for fuel and an outlet therefor to the main burner, a safety valve controlling the passage of fuel between the inlet and outlet, a main control valve in said casing between said safety valve and the outlet, means for adjusting said main control valve between "off" and "on" positions and a position intermediate thereto, said main control valve being adapted to permit the passage of fuel from the safety valve to both the main and pilot burners when in said "on" position and to the pilot burner only when in said intermediate position, means operable in said intermediate position of the main control valve for conducting fuel to the pilot burner when the safety valve is closed, and means responsive to the presence of a flame at the pilot burner for opening the safety valve for passage of fuel therethrough to said pilot burner while the main control valve remains in said intermediate position, and to both the main and pilot burners when the main control valve is adjusted to said "on" position.

8. A safety control for gaseous fuel burners having main and pilot burners, comprising in combination, a safety valve controlling the passage of fuel to both the main and pilot burners, a main control valve having a chamber therein providing a passage for fuel from said safety valve, means for establishing communication between said chamber and both the main and pilot burners when the safety valve is in open position, and means for by-passing fuel through said chamber to the pilot burner only, when the safety valve is in closed position.

9. A safety control for gaseous fuel burners having main and pilot burners, comprising in combination, a safety valve controlling the passage of fuel to both the main and pilot burners, a main control valve movable between positions and having a chamber therein providing a passage for fuel from said safety valve, a port in said main control valve providing in one of said positions thereof an outlet for passage of fuel from said chamber to the main and pilot burners when the safety valve is in open position, and means effective in another said position of the main control valve for by-passing fuel through said port and chamber to the pilot burner only, when the safety valve is in closed position, said by-pass means being rendered ineffective by said main control valve in moving to said one position thereof before said passage of fuel from the chamber to the main burner can occur.

10. A safety control for gaseous fuel burners having main and pilot burners, comprising in combination, a casing having an inlet for fuel and an outlet therefor leading to the main and pilot burners, a safety valve controlling the passage of fuel from said inlet, a main control valve having a port movable therewith into and out of registry with said outlet to control the passage of fuel from said safety valve, a by-pass passage in said casing providing communication between said inlet and the pilot burner when said safety

valve is closed, manual means for moving said main control valve to a position to open said by-pass for passage of fuel to said pilot burner, and means responsive to the presence of a flame at the pilot burner for opening the safety valve, said manual means being operable for moving said main control valve to another position for closing said by-pass and simultaneously establishing communication between said port and the outlet for passage of fuel from the inlet to both main and pilot burners.

11. A safety control for gaseous fuel burners having main and pilot burners, comprising in combination, a casing having an inlet for fuel and an outlet therefor to the main burner, a safety valve controlling the passage of fuel between the inlet and outlet, a main control valve in said casing between the safety valve and the outlet having an axial opening providing a passage for fuel from said safety valve, a transverse port in said main control valve communicating with said opening and the outlet, a duct in said casing communicating with said inlet and said port when the main control valve is in one position, a second duct in said casing communicating with said pilot burner and said port when said main control valve is in said position, said ducts providing passage for fuel from the inlet to the pilot burner when the safety valve is closed, means for opening said safety valve when said main control valve is in said position for passage of fuel therefrom through said second duct to said pilot burner, and means on said main control valve to close the first said duct from communication with said port while retaining communication with said second duct upon movement thereof to another position.

12. A safety control for gaseous fuel burners having main and pilot burners, comprising in combination, a casing having an inlet for fuel and an outlet therefor leading to the main burner, a safety valve controlling the passage of fuel between said inlet and outlet, a main control valve in said casing between the safety valve and the outlet having a chamber for fuel from said safety valve, a port in said main control valve communicating with said chamber and the outlet, a duct in said casing communicating with said inlet and said port when the main control valve is in one position, a second duct in said casing communicating with said pilot burner and said port when said main control valve is in said position, said ducts providing passage for fuel from the inlet to the pilot burner when the safety valve is closed, manual means for moving said main control valve to said position, means responsive to the presence of a flame at the pilot burner when the main control valve is in said position for opening the safety valve, and means on said main control valve to close the first said duct from communication with said port while establishing communication with said outlet and the second duct upon operation of said manual means to move said valve to another position.

THOMAS H. JEFFERS.
